Attorney

UNITED STATES PATENT OFFICE.

CHRISTIAN A. BUSCHAM, OF IRVINGTON, NEW JERSEY, ASSIGNOR TO C. A. BUSCHAM
MFG. CO., OF IRVINGTON, NEW JERSEY.

VANITY CASE.

Application filed September 10, 1923. Serial No. 661,925.

To all whom it may concern:

Be it known that I, CHRISTIAN A. BUSCHAM, a citizen of the United States, residing at #580 Lyons Avenue, in the town 5 of Irvington, in the county of Essex and State of New Jersey, have invented certain new and useful Improvements in Vanity Cases, of which the following is a specification.

10 This invention relates to toilet articles, and has special reference to a vanity case or dressing.

One important object of the invention is to improve the general construction of devices of this character.

A second important object of the invention is to provide a device of this character wherein the case is so constructed as to provide a rouge receptacle and a powder receptacle, the latter being slidable to and from over the rouge receptacle, and thus constituting a cover therefor, thus obviating the difficulty found with the ordinary type of vanity cases wherein the powder receptacle 20 is hinged to hold powder on one side and the rouge on the other, and wherein frequent dropping of the cosmetics results.

A third important object of the invention is the construction of a device of this character made entirely from sheet metal so that it can be economically produced.

With the above and other objects in view as will be hereinafter apparent, the invention consists in general of certain novel details of construction and combinations of parts hereinafter more fully described, illustrated in the accompanying drawings and specifically claimed.

In the accompanying drawings like characters of reference indicate like parts in the several views, and:

Fig. 1 is a top view of the improved device with the cosmetics removed, and showing the powder receptacle in its closed position.

Fig. 2 is a view similar to Fig. 1 showing the powder receptacle moved to open position and exposing the rouge receptacle.

Fig. 3 is a detail view showing the struck up lugs which hold and guide the powder receptacle.

Fig. 4 is an enlarged detail view on the line 4-4 of Fig. 1.

The invention consists in its present form 55 of a cylindrical box having a bottom 10 and

side walls 11. To this box is hinged a hollow cover 12, the hinge being indicated at 13. Fitted within this box is a plate 14 having a depending flange 15 around its periphery, this flange being of such height 60 that it brings the plate 14 substantially flush with the upper edge of the box side 11. In this plate is also formed a rouge receiving well, the plate being provided with a circular aperture 16 disposed eccentrically of the 65 plate and lying adjacent the hinge 13, the aperture being provided with a depending flange 17 forming the side wall of the well, and extending to the bottom 10. Adjacent to the front of the device, that is to say, the 70 side opposite the hinge, there is provided a pair of lugs 18 which are struck up from the metal of the plate and extend through slots 19 which are arranged in parallelism and are rectilinear, these slots being formed 75 in the bottom 20 of a powder receptacle having a side wall 21, the diameter of this receptacle being less than the diameter of the plate 14. By means of this construction the bottom of the powder receptacle constitutes 80 a cover for the rouge well when the receptacle is slid in, as in Fig. 1, and exposes the rouge well for access when the receptacle is slid out, as in Fig. 2. In order to hold the 85 powder cake out of contact with the lugs 18, the bottom 20 has secured thereon a liner plate 22. It will be noted that the ends of the lugs 18 are turned over so as to prevent 90 accidental displacement of the powder receptacle.

It will be obvious that when the powder receptacle is in the position shown in Fig. 1, the top 12 is folded down thereover, and forms a housing therefor, as shown in dotted lines in Fig. 4. In order to center the 95 powder receptacle on the plate 14 and thus permit the top to shut down, there is provided adjacent the hinge an arcuate stop rib 23, which is fixed to the plate 14.

The usual mirror 24 is also provided in the 100 top.

It will be seen from the foregoing, that both the rouge and the powder may be exposed at the same time if desired, and that the construction of the device is extremely 105 simple and yet convenient.

There has thus been provided a simple and efficient device of the kind described and for the purpose specified.

It is obvious that minor changes may be 110

made in the form and construction of the invention without in any way departing from the material spirit thereof. It is not, therefore, desired to confine the invention to the exact form herein shown and described, but it is wished to include all such as properly come within the scope claimed.

Having thus described the invention, what is claimed as new, is:

- 10 1. A vanity case including a case bottom having a hollow top hinged thereto at one side, a well in said case bottom for the reception of a cosmetic, a cosmetic receptacle fitted on top of the case bottom and having rectilinear sliding connection with said bottom, said receptacle forming a cover for said well when slid inwardly and being housed in the top upon closing of the latter on the case bottom, and an arcuate stop fixed on said case bottom to limit the movement of said receptacle.
- 15 2. A vanity case including a case bottom having a hollow top hinged thereto at one side, a well in said case bottom for the reception of a cosmetic, a cosmetic receptacle fitted in top of the case bottom and having rectilinear sliding connection with said bottom, said receptacle forming a cover for said well when slid inwardly and being housed in the top upon closing of the latter on the case bottom, said well being disposed eccentrically of the case bottom, and adjacent to the hinge of the top and the receptacle sliding toward and from said hinge, and an arcuate stop fixed on said case bottom to limit the movement of said receptacle.
- 20 3. A vanity case comprising a hollow cylindrical box open at the top, a hollow cylindrical main cover fitting on said box, a hinge connecting said main cover and said box at one side, a plate having a downwardly turned peripheral flange fitted in said box and filling the same whereby the plate lies substantially flush with the edge

of the box, said plate having an eccentric opening therein adjacent the hinge and a depending flange around the periphery of the opening to form a well for reception of a cosmetic, said plate further having a pair of spaced lugs adjacent the edge of the plate opposite the hinge, a second open topped box mounted on said plate and being of less diameter than the plate, said second box being provided with a bottom having parallel rectilinear slots for the reception of the lugs, the ends of said lugs being bent over to retain the second box in position, and liners disposed in the bottom of the second box to hold an article contained therein free of said lugs.

4. A vanity case comprising a hollow cylindrical box open at the top, a hollow cylindrical main cover fitting on said box, a hinge connecting said main cover and said box at one side, a plate having a downwardly turned peripheral flange fitted in said box and filling the same whereby the plate lies substantially flush with the edge of the box, said plate having an eccentric opening therein adjacent the hinge and a depending flange around the periphery of the opening to form a well for reception of a cosmetic, said plate further having a pair of spaced lugs adjacent the edge of the plate opposite the hinge, a second open topped box mounted on said plate and being of less diameter than the plate, said second box being provided with a bottom having parallel rectilinear slots for the reception of the lugs, the ends of said lugs being bent over to retain the second box in position, liners disposed in the bottom of the second box to hold an article contained therein free of said lugs, and an arcuate rib extending up from said plate adjacent the hinge and forming a stop for said second box.

In testimony whereof I affix my signature.

CHRISTIAN A. BUSCHAM.
